UNITED STATES PATENT OFFICE.

CARL L. DINGENS, OF NEW YORK, N. Y., ASSIGNOR TO THE BIGELOW BINDER COMPANY, OF NEW YORK, N. Y., A CORPORATION OF NEW YORK.

BINDER.

1,161,632.

Specification of Letters Patent. Patented Nov. 23, 1915.

Application filed March 3, 1913. Serial No. 751,784.

To all whom it may concern:

Be it known that I, CARL L. DINGENS, a citizen of the United States, residing at New York city, county of New York, and State of New York, have invented certain new and useful Improvements in Binders, fully described and represented in the following specification and the accompanying drawings, forming a part of the same.

10 This invention relates to certain improvements in temporary binders, and particularly to those intended for use with magazines or pamphlets which are provided with special holding tabs or clips.

15 It is one object of the invention to provide an improved binder in which a single magazine may be firmly held in such a way that the leaves may be easily turned and will lie flat as if unbound, which will not be

20 more clumsy to handle than the magazine itself, and from which the magazine cannot be readily taken by readers in public libraries and the like.

It is a further object of the invention to provide an improved construction for securing a magazine which will require the manipulation of but a single member to position the magazine and to release it.

It is a further object of the invention to provide a construction of simple design which shall be compact, cheap to make, and durable.

These objects are effected generally by providing a support secured between the covers of the binder provided with holding projections or tongues fast on the support, over which tongues tabs or clips attached to the magazine to be bound may be slipped, and a locking member coöperating with the support for holding the tabs in position on the tongues, so that only a single movement of the locking member is necessary to lock the tabs in position or release them. The support and locking member are furthermore so formed and arranged that the magazine is held snugly in the covers, and is held only by its back edge, so that its sides are not compressed and it will open flat.

A full understanding of the invention can best be had from a detailed description of a binder, which will be given in connection with the accompanying drawings, in which—

Figure 1 is a front view of the binder open and showing the parts in position to receive a magazine, certain portions being

broken away to show the construction; Fig. 2 is a vertical section partly broken away taken on line 2—2, Fig. 1, showing a magazine with holding clips or tabs ready to be locked in position; Fig. 3 is a cross section taken on line 3—3, Fig. 2, showing the binder in closed position with a magazine held therein; Fig. 4 is a view taken on line 4—4, Fig. 2, of the holding plate and locking slide co-operating therewith; Fig. 5 is a partial vertical section partly broken away, showing a magazine with holding clips or tabs in locked position; Fig. 6 is a detail face view of the other side of the plate shown in Fig. 4 showing one of the holding tabs slipped over a tongue on the plate, and locked in position, and showing also a magazine fast in position, the magazine being shown as tipped to one side. Fig. 7 is a detail cross section on line 7—7 of Fig. 1, showing a preferred form of securing the plate and slide to the covers.

Referring now to these drawings, the binder includes a pair of covers 1 which are flexible, if desired, between which is inserted preferably a stiffening member as a half-round of wood or other suitable material 2, having a straight inner face. The half-round 2, when employed, forms a convenient base on which to secure the support and locking member, though such parts may be secured between the covers otherwise.

The particular construction of the support on which are the holding projections may be somewhat varied. As shown, this support is a light metal plate 3 provided with side flanges 4 and end flanges or abutments 5, these flanges being formed on one face of the plate, the other face of the plate being straight and smooth, as shown. The plate is secured to the base 2 in any suitable manner, as by screws 13, passing through suitable holes made in the outer face thereof.

To provide a neat and easily handled construction, the plate is made narrow, as shown, and in the preferred construction the locking member is located behind the plate, between the plate and the half-round. In order that the back of the magazine may be held snugly in the binder, the holding projections or tongues are formed thereon so as not to project beyond the face of the plate. The tongues may be so formed in various ways. A convenient construction, and

one easily manipulated, is that shown, in which the tongues are formed so as to extend in a plane slightly behind the plane of the outer surface of the plate, so that they 5 may be engaged by tabs or clips and the latter locked in position by the locking member, the back of the magazine being thus held snug and firm against the plate. As 10 illustrated, there are two of these tongues 6, 7, formed integral with the plate by stamping or cutting out the metal, and bending the tongues back away from the face of the plate, recesses 8 being left which permit the 15 tabs or clips 9 to be slipped over the tongues as shown in Fig. 3. The front side of the ends of the tongues may be beveled, if desired, as shown at 10, Fig. 3, for a purpose hereinafter referred to. Coöoperating with the plate to hold the tabs or clips firmly on 20 the tongues is a locking member, the construction of which may be somewhat varied. This member will, however, preferably have a sliding movement relatively to the plate, and preferably will be secured thereto so 25 that a slight longitudinal movement of the member will lock or release the clips to or from the tongues. A convenient construction is that shown in which the locking member is a thin plate or bar of light metal 30 11, positioned between and adapted to slide on the side flanges 4 of the plate 3, and held in position between the plate and the half-round by the screws 13 by which the plate 3 is secured to the half-round, suitable elongated slots 12 being provided in the locking member to permit the longitudinal movement of the bar. The locking bar 11 is recessed at 14 for substantially its full width, narrow strips being left at the sides of the 35 recesses, these recesses corresponding with the recesses 8 in the plate 3, through which recesses the clips 9 can project when in position on the tongues as shown in Fig. 3. The recesses 14 are extended longitudinally of 40 the plate a somewhat greater distance than is necessary to admit the clips, as shown, but the extending portions are not as wide, locking shoulders 15 being formed which, when the plate is moved upwardly from the position 45 shown in Fig. 4 pass over the tongues and hold the clips thereon. The slide bar 11 is prevented from sliding out of the plate 3 by the end flanges 5, which act as abutments for an inturned flanged end 16 on the 50 bar. By positioning the bar 11 between the plate 3 and the half-round 2, the bar is more or less concealed and not readily manipulated by the fingers. The bar may, if desired, be provided with a projection or knob 55 30 located on the side of the bar near its end (see Fig. 4) and projecting through the flange 4, but in the preferred construction shown is manipulated by a suitable tool, such as a pin inserted in small holes 17 in 60 65 the end flanges 5 of the plate 3, the pin push-

ing against the flange 16 on the bar and giving it a sufficient movement to unlock the binder. Shoulders 15 may be formed with beveled engaging surfaces as indicated at 18, Fig. 3, which co-operating with the beveled tongue ends facilitate the engagement of the parts.

It is desirable that provision be made for accommodating the ends of the tabs or clips which project beyond the tongues when the tabs are in position. While this might be done by making the plate 3 and bar 11 of sufficient thickness, preferably, in order to keep the parts as compact and in as small a compass as possible, the base 2 is recessed 80 behind the tongues as at 19 in Fig. 3.

Various forms of tabs or clips may be employed. A convenient one and one easily put in place, is shown in Figs. 2 and 5, such clips consisting of a thin sheet of metal having a head 20 adapted to be inserted through the back of a magazine and wings 21 extending from each side of the head holding the clips in the magazine and forming a firm means of attachment to the tongues. 85 90

In use, the clips, unless means are provided to prevent it, are apt to be pushed back between the leaves of the magazine when being placed on the tongues, becoming lost between the leaves and difficult to find. Means are accordingly provided whereby the clips are held against such accidental displacement. In the preferred construction, these clips are provided on one or both of their side surfaces with projections or barbs 31 formed conveniently by striking up points of metal which preferably point away from the head of the clips and act to prevent the clips from becoming displaced when the magazine is inserted in the binder, the points biting into the paper.

With the construction described, the magazine is held firmly in the binder and may be released therefrom by simply sliding the locking bar, and furthermore being held only at the back, with no compression on the sides, the magazine will unfold and lie as flat as if not bound, a very desirable advantage in binders of this type. The particular construction shown and described has been found a desirable one, but it will be understood that certain changes and variations may be made without departing from the invention. 110 115

What I claim is:—

1. In a temporary binder, the combination with a pair of covers, of a base between the covers, a plate secured to the base, said plate having side flanges turned toward the base, tongues integral with the plate, and a slide bar movable between the side flanges of the plate and adapted to coöperate with the tongues to hold in position tabs or clips slipped over the tongues.

2. In a temporary binder, the combination 130

tion with a pair of covers, of a recessed base, a plate secured to the base and provided with side flanges, holding tongues fast on the plate and extending inwardly therefrom away from the plane of the face of the plate, and a slide bar positioned between the flanges and adapted to coöperate with the tongues for holding in position tabs or clips slipped over the tongues the ends of the tabs or clips projecting into the recesses of the base.

3. In a binder, the combination with covers, of a support located between the covers, holding projections fast on the support, a locking member movable on the support and adapted to coöperate with the holding projections to hold in position tabs or clips slipped over them, and means requiring the use of a tool for moving the locking member to unlock it from the holding device.

4. In a binder, the combination with covers, of a plate located between the covers, holding devices fast on the plate, said plate being provided with side flanges and end flanges, a locking member interposed between the plate and the covers and movable between the flanges and adapted to coöperate with the holding devices, said end flanges being formed with holes through which a tool may be inserted to move the plate.

5. A single number pamphlet binder hav-

ing a pair of covers, a base secured between the covers, a light metal plate 3 secured to the base and cut or stamped to provide integral tongues 6, the recesses 8 at the sides 35 of the tongues being left so that clips may be slipped over them, and a locking member for locking the clips on the tongues.

6. A single number pamphlet binder having covers, a base secured between the covers, a light metal plate 3 secured to the base stamped or cut to form integral tongues 6 with recesses 8 at the sides of the tongues so that clips may be slipped over them, and a slide bar 11 having tongue engaging 45 shoulders for locking the clips on the tongues.

7. In a binder, the combination with a pair of covers, of a plate secured between the covers and having holding tongues, and a locking member inclosed by said plate and movable with respect thereto and adapted to coöperate with said tongues to hold in position tabs or clips slipped over the latter.

In testimony whereof, I have hereunto set my hand, in the presence of two subscribing witnesses.

CARL L. DINGENS.
